(57) **CLAIM**

The ornamental design for a loudspeaker, as shown and described.

DESCRIPTION

FIG. 1 is a perspective view of a loudspeaker showing my new design;

FIGS. 2-7 are illustrated as if the overall conical shape is disposed with its central axis in a horizontal orientation and are described relative to this orientation;

FIG. 2 is an elevational view of the front face thereof;

FIG. 3 is a side elevational view of one side thereof;

FIG. 4 is a side elevational view of the opposite side thereof;

FIG. 5 is a top plan view thereof;

FIG. 6 is bottom plan view thereof; and,

FIG. 7 is a rear elevational view thereof.

The line shading on the conical body is intended to depict translucency or transparency. The broken line showings form no part of the claimed design.
